UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

MINING APPARATUS.

1,378,359.

Specification of Letters Patent. Patented May 17, 1921.

Application filed February 23, 1915, Serial No. 9,972. Renewed July 15, 1920. Serial No. 396,590.

To all whom it may concern:

Be it known that I, NILS D. LEVIN, a citizen of the United States, residing at Columbus, in the county of Franklin and State of Ohio, have invented certain new and useful Improvements in Mining Apparatus, of which the following is a specification, reference being had therein to the accompanying drawings.

10 This invention relates to mining apparatuses of the class in which each comprises a cutting mechanism which is bodily movable transversely across the front of a room while cutting and a wheeled truck for carrying the mechanism from one place of use to another. According to usual earlier practice it has been necessary to unload the cutting mechanism from the truck and then to move it into cutting position by means of 15 bars, cables, etc.; and then, after the completion of the cutting operation, it has been necessary to again move the machine by means of bars, cables, etc., back to the position from which it can be reloaded. According 20 to the present invention, the truck is so constructed that the mining machine can be unloaded therefrom into any desired cutting position or reloaded thereonto from any desired cutting position without any 25 intermediate movements being necessary.

The preferred form of machine embodying the invention belongs to that class in which each has the movements of its cutting mechanism guided and largely controlled 30 by means of a wheeled truck which remains on a track throughout the cutting operation and is preferably anchored against movement. Earlier machines falling within the above given definition have been proposed 35 prior to my present invention, but in these earlier machines dependence was placed largely or entirely on the truck itself for the carrying of the weight of the entire apparatus, including the cutting mechanism, 40 not only during transportation but also during the cutting. With the weight carried by the truck it was impractical to permit the cutting mechanism to project beyond the outlines of the base through more than 45 a certain relatively small distance, and consequently the width of the room or entry which could be cut by one of the earlier machines was quite limited.

One object of my invention is to provide

an apparatus having the truck parts so arranged and connected that the machine can be loaded directly onto the truck by power from any cutting position without being first moved along the floor into a predetermined loading position. 55

Another object of the invention is to provide an apparatus in which the cutting mechanism can be carried on the truck during transportation and in which it is movable horizontally therefrom without breaking its connection therewith to rest entirely upon the floor and be moved horizontally under the guidance and control of the truck to cut a horizontal kerf from one side to the other of a relatively wide room. Other 60 objects of the invention are to provide certain improved structural and mechanical features whereby the above mentioned objects are carried out to the best advantage. A further object is to provide a mining 65 machine truck adapted to carry a mining machine and having devices permitting loading of a machine from any position and preferably also adapted for guiding and controlling the machine when it is supported 70 independently of the truck. 75

In the accompanying drawings I have shown, for purposes of illustration, one embodiment of the invention, but it will be understood that many changes may be made 80 in the construction shown without departing from the spirit of my invention.

Of the drawings,

Figure 1 is a side view of the complete apparatus, with the cutting mechanism in 85 operative position.

Fig. 2 is a plan view of the machine as shown in Fig. 1.

Fig. 3 is a side view of the apparatus, with the parts so arranged as to be adapted 90 for transportation.

Fig. 4 is a plan view of the main base part of the truck with some of the mechanism carried directly thereby. In this view the swinging supporting and guiding 95 devices for the cutting mechanism are removed.

Fig. 5 is a plan view of the supporting and guiding devices for the cutting mechanism.

Fig. 6 is a transverse sectional view taken along the line 6—6 of Fig. 3.

Fig. 7 is a fragmentary side elevation

taken partly in section along the line 7—7 of Fig 6.

Fig. 8 is a fragmentary side view showing the cutting mechanism in one of its intermediate positions.

Fig. 9 is a fragmentary side view taken oppositely to Fig. 3 and showing the means for locking the mining machine to its supporting pan.

10 Figs. 10 and 11 are fragmentary views showing details of the supporting and guiding devices for the cutting mechanism.

15 Figs. 12 and 13 are diagrammatic side views showing the positions which the parts of the apparatus assume during the movement of the cutting mechanism into operative position.

20 Figs. 14 to 24 are diagrammatic plan views showing the steps incident to the operation of the machine in the cutting of a kerf across the front of a room.

25 Figs. 25 and 26 are diagrammatic plan views showing the positions which the machine assumes when operated according to another plan.

30 Referring to the drawings, A represents a track which is preferably laid down along the center of the room or entry, or other space, across the front of which the cutting operations are to be carried on. B represents the mining apparatus as a whole, it comprising a cutting mechanism C having driving and feeding devices at D, a truck or abutment H mounted on the track A, and 35 devices E, F and G pivotally connected with the truck or abutment H and adapted to be engaged by the cutting mechanism for loading and unloading and preferably also serving to guide the cutting mechanism during 40 its horizontal cutting movements.

45 The truck H, to which the skid or guide devices E, F and G are connected, has a main body frame consisting of the longitudinal side bars 1, 1 and the cross bars 2, 3 and 4. The body is mounted upon the axles 7 and 8 to the ends of which are secured the track wheels 9, 9 resting upon the rails 10, 10 of the track A. The axles are mounted in bearings 6, 6, which are adjustable longitudinally by means of the screws 6^a, 6^a. The two axles are connected together by means of a chain 11, which passes over sprocket wheels secured to the ends of the axles. At the other end of the rear axle 8 50 there is secured another sprocket wheel over which passes a chain 12. This chain extends upward and rearward and engages a sprocket wheel 12^a loosely mounted on a transverse shaft 12^b which extends through 55 a casing 5 mounted on the truck frame. The parts mounted in the casing 5 and immediately adjacent thereto are preferably the same as those shown in my copending application for mining machine trucks Serial No. 825,369, filed March 17, 1914. A 60

very brief description of these parts will here be sufficient. 15 is a power receiving bevel pinion mounted on a longitudinal shaft 15^a at the rear end of which is another bevel pinion 15^b. This bevel pinion 15^b 70 meshes with the two bevel pinions 15^c and 15^d loosely mounted on the said shaft 12^b. Between the respective pinions 15^c and 15^d and the shaft there are provided disk clutches 15^e and 15^f which can be thrown 75 into engagement alternately by means of the lever 14. The sprocket wheel 12^a can be connected with the shaft 12^b by means of the clutch 13 which is controlled by the swinging lever 13^a. It will be seen that the gears 15^c and 15^d, together with the clutches 15^e and 15^f constitute a reversing mechanism whereby the motion of the power receiving gear 15 can be transmitted to the axles and track wheels in either direction. 85

90 The skids or controlling devices for the cutter or cutting mechanism have a connection with the truck or abutment frame which permit them to move relatively to the truck in a fixed path; and as the cutter is connected with the skids it also can be caused to move in a corresponding fixed path. Preferably the connection with the truck is a vertical pivotal one, and this is the construction illustrated. Secured to the frame 95 of the truck is a sheet metal plate 16 near the center of which there is preferably a large circular aperture. Bolted or riveted to the plate 16 below the central part thereof is a circular spider 17. Around the periphery of the spider there are mounted rollers 18, 18 rotatable on horizontal radial pivot pins 19, 19. The spider 17 has spokes 21, 21 which carry at the center an apertured hub 22. 20 is a flat metal plate positioned to 100 rest directly upon the rollers 18, 18, and it is provided with a depending flanged ring 23 firmly riveted in place. A pivot block 24 is provided which is seated in the aperture in the aforesaid hollow hub 22 and 105 which closely fits the inner surface of the ring 23. The pivot block is held in place by means of a bolt 24^a and it is provided at 26 with a flange which engages the ring 23 to hold the plate 20 and the parts connected with it against movement upward 110 away from the truck. 115

120 The guiding and controlling means is constructed to permit the cutter or mining machine to be supported on the ground or floor independently of the truck. As shown, in addition to having a vertical pivotal connection with the truck frame, it preferably has two horizontal pivotal joints by which its elements are connected together. The details of the guiding and controlling means will now be described.

125 The plate 20 is provided along its sides with reinforcing angle bars 27, 27. these parts constituting the device E mentioned 130

above. At the forward end of the device E and secured to the angle bars 27, 27 are brackets 27^a, 27^b, and through apertures in these brackets there extends a transverse 5 pivot pin 27^b.

The aforesaid device F comprises two longitudinal side bars 29, 29, a rear transverse connecting plate 30 and a front transverse connecting plate 30^a. Secured to the 10 under side of the plate 30 are brackets 30^b which are apertured to receive the aforesaid pivot pin 27^b. It will be seen that by the construction described the two devices are horizontally pivoted so as to be relatively 15 movable. Riveted to the plate 30 is a tail plate 31 which extends rearward. The plate 20 is recessed or notched to receive the rear part of the said plate 31. Secured to the forward ends of the bars 29 are brackets 20 or shoes 32, 32 to which the aforesaid plate 30^a is secured, this plate being curved longitudinally, as clearly indicated in Figs. 1, 3, 8 and 11.

The aforesaid device G comprises a bottom plate 34 and side angle bars 35, 35. This device G carries the cutter, *i. e.* the cutting mechanism and the driving and feeding devices therefor. The pan G is provided at its forward end with shoes 44, 44, which 30 are rounded at their forward ends. At the rear end of the pan G there are provided means for pivotally connecting the pan with the forward end of the device F. Preferably the parts of the guiding and controlling means, in addition to having horizontal pivotal joints, also engage one another telescopically so that they can rest one upon another and be supported on the truck. In the construction shown the pan G is slidable relatively to the devices F and E. At the rear 35 end of the pan are hook-like castings 45, 45, which rest upon and embrace the vertical walls of the angle bars 29, 29, as shown in detail in Figs. 10 and 11. The hooks 45, 45 can slide along the bars 29, 29, but when the pan is in its outermost position, with the hooks lowermost, the extensions 46 formed on the hooks will enter sockets 47 provided in the shoes 32, 32, as indicated in Fig. 8, 45 thus providing a horizontal pivotal joint. For holding the hooks in the sockets suitable pins 48 are provided which can be put in place or removed as desired.

The extension 46 on one of the castings 45 (as, for instance, the right hand one) also serves in conjunction with an upright stop 46^a on the bed frame of the truck to prevent movement of the machine about the vertical pivotal axis when the apparatus is adjusted for transportation. By referring to Fig. 9 it will be observed that the stop 46^a extends between the extension 46 and the corresponding angle bar 29 when the pan is in its rearmost position.

65 The invention is not limited to a cutter of

any particular sort, but there are many advantages incident to the use of a complete separately operable mining machine which can be connected to the guiding and controlling devices or which can be disconnected from them and used independently. I have shown a standard mining machine of the "short wall" type, although the invention is not limited in this respect. The machine shown is similar to that shown and described in my copending application for mining machines, Serial No. 825,370, filed March 17, 1914. For details of the construction reference can be had to the said application, and it will be sufficient here to refer briefly to the more important parts. 37 is the main frame of the mining machine and 38 is the main driving motor which is suitably mounted on the frame. The cutting mechanism is indicated, as a whole, by 39, it being of the well known chain type. Power is transmitted to the driving sprocket 39^a for the cutter chain through the gears 38^a, 38^b, 38^c and 38^d. The vertical shaft on which the sprocket wheel 39^a and the gear 38^d are mounted also carries a worm 38^e which meshes with a worm wheel 38^f on a transverse shaft suitably mounted at the rear of the machine. Loosely mounted on this shaft is a cable drum 42 which can be connected to the shaft by means of the friction clutch 42^a controlled by the hand wheel 42^b. 43 is a cable wound upon this drum 42 and adapted to be used in the manner to be hereinafter described. 40 is another drum which is mounted on a suitable transverse shaft 40^a. This shaft is driven from the transverse shaft which carries the drum 42 by means of the gears 40^b, 40^c, 40^d and 40^e. The gear 40^b is loosely mounted on the shaft and can be connected thereto by means of the friction clutch 40^f controlled by the hand wheel 40^e. It will be observed that the gearing is such that the two drums 42 and 40 will be driven at different speeds, the drum 42 being driven relatively rapidly and the drum 40 relatively slowly. 41 is a cable wound upon the drum 40 and adapted to be used in the manner hereinafter described.

The pan G is of sufficient length to support the mining machine from end to end, as clearly shown in Fig. 8. The mining machine is slidable along the pan and its movement outward is limited by means of the stop 34^a shown in Fig. 5, and its movement inward is limited by the surfaces 45^a formed on the hook castings 45. For temporarily locking the mining machine in its rearmost position with respect to the pan, for a purpose which will presently appear, there is provided a link 39^a connected to the rear part of the machine and adapted to be slipped over an upward projecting lug 39^b on the pan. This lug 39^b is provided with an aperture 39^c into which one of the pins 130

48 can be inserted to hold the link against disengagement from the lug. These parts are clearly shown in Fig. 9.

5 For locking the machine in the position shown in Fig. 3 there is provided a latch 37^a adapted to enter a socket 27^c on the device E.

10 It will be seen that the connection between the truck and the cutter or mining machine through the devices E, F and G always remains unbroken, and the said devices are always ready to guide the machine onto the truck from any position in which it may be independently supported.

15 49 is a cable reel of suitable form mounted on the rear part of the truck H. The reel is driven by means of a rope which passes over the sheave 50 secured to the shaft 12^b and a sheave 51 secured to the reel itself.

20 The main cable, which is wound upon the reel, is indicated by 52, this cable extending outward along the track to a suitable permanent electric conductor to which it is attached. Current is supplied from the 25 cable 52 and from the reel to the motor 38 of the mining machine by means of the long flexible cable 53 which permits relative movements of the mining machine in the manner to be hereinafter described.

30 For guiding the cable 43, which is wound upon the drum 42, a suitable system of guide sheaves is provided. As shown, this comprises a sheave 54 rotatable about a horizontal axis, a sheave 54^a, which is rotatable about a horizontal axis and which can swing bodily around a vertical axis of the machine over either of which the cable can pass according to the position of the sheave 54^a. From one or the other of the sheaves 55 or 35 40 55^a the cable can be extended forward and its forward end can be secured to one of the hooks 56 or one of the hooks 57, according to the position of the machine on the supporting and guiding devices. Instead of being attached to one of the aforesaid hooks, the cable 53 can be positioned as shown in Figs. 1 and 2, that is, it can be passed over the guide sheaves 58 and 59 and carried backward into engagement with a hook 60 45 50 on the device E.

The rope 41 wound on the drum 40 can also be carried forward over the said sheaves 58 and 59 for use in a way to be described.

55 Fig. 3 shows the machine with the parts arranged for transportation from place to place about the mine. The power receiving bevel pinion 15 of the truck is in engagement with the large bevel gear 40^b of the mining machine. The mining machine motor is operated and power is transmitted from it through the gears 38^a, 38^b, 38^c and 15 to the bevel gearing in the casing 5 from which it is transmitted through one or the other of the friction clutches to the chain 60 65 12 and thence to the truck wheels them-

70 selves. By means of the lever 14 and the clutches controlled thereby the direction of rotation of the truck wheels can be reversed and the truck driven in either direction. The electric current for the motor 38 is supplied in the way before described through the main cable 52 and the auxiliary connecting cable 53. The cable 52 is wound and unwound automatically as the truck moves backward and forward. 75

According to the preferred way of using the machine, as shown in Figs. 14 to 24, it is advanced into a mine or entry along the central track A therein to a position such as that indicated in Fig. 14, and there it is stopped and the chain 12 is removed, thus making it possible for the mining machine and the supporting devices therefor to be swung horizontally about the vertical pivotal axis. Then the cable 43 is unwound from the drum 42 and carried around the sheaves 54^a and 55 and is attached to the hook 56 and the drum is turned by means of power from the motor 38 and the machine is drawn forward a short distance to the position indicated diagrammatically in Fig. 14. This slight forward movement of the machine disengages it from the stop 46^a and permits it to be swung about the vertical pivot. As soon as the machine is disengaged from this 95 stop it is swung so that the parts lie in the relative positions indicated in Fig. 15. The winding of the cable is continued and the mining machine, with its pan, is moved outward to the position indicated in Fig. 16. It will 100 be seen that the link 39^a engaging the lug 39^b causes the pan G to travel forward with the machine. At about the time that the machine and the pan reach the relative positions shown in Fig. 16 they swing downward 105 by gravity about the pivotal axis at 27^b to the positions shown in Fig. 12. The winding of the cable 43 is continued and the pan and the machine continue to move forward, the forward end of the pan sliding along the 110 ground on the shoes 44 and the rear end of the pan sliding down the inclined section F supported on the castings 45. This movement is continued, the parts moving through the position shown in Fig. 13 and finally 115 reaching the position shown in Fig. 17. Then the pins 48, 48 are inserted to lock the pan to the guide device F.

When the parts have reached this position, as shown in Fig. 17 the truck is locked 120 in position by blocking the wheels thereof and by putting in place a jack 61 with its lower end engaging the socket 24^a formed in the pivot block 24 and with its upper end engaging the roof. In this way the truck 125 part of the machine is firmly held down upon the track and is prevented from moving bodily horizontally in any direction. However, as the lower end of the jack engages a non-rotary element there is no inter- 130

- ference with the free swinging movement of the mining machine and the guiding devices therefor. With the parts in the position as shown, the cable 43 is detached from the hook 46 and the cable 41 is carried forward from the drum 40 and is connected to the hook 57. The link 39^a is removed from the lug 39^b and power is applied to rotate the drum 40 and thus draw the machine bodily 5 forward along the pan to the positions indicated in Figs. 18 and 19. It will be understood, of course, that in moving forward the cutters are operated and act to make a "sumping" cut into the coal, as indicated. 10 After the cutting mechanism has cut its way into the coal for its entire length the feeding is stopped and the cable 41 is removed from the hook 57 and is carried over the guide sheave 59 and to a jack at the other side of 15 the room, as indicated by 62 in Fig. 20. The winding of the cable is again started and the cable now serves to draw the machine transversely across the room, it swinging about the vertical pivotal axis on the truck. 20 Successive positions are shown in Figs. 21 and 22.

After the cut has been completed the cable 41 is removed from the sheave 58 and the cable 43 is again brought into use. This 30 cable is carried forward around the same sheave 59 and back into engagement with the hook 60 on the truck body. This arrangement of the cable is shown diagrammatically in Fig. 23 and in detail in Figs. 35 1 and 2. The pins 48, 48 are removed to release the pan and the cable is then wound to draw the machine backward. The machine first moves backward along the pan, and then the pan itself, with the machine, 40 slides up the inclined guiding device F. The engagement of the pan with the tail plate 31 causes the lower end of the device F to swing upward and the moving of the pan and machine backward along the device F 45 is continued until finally the center of gravity is so positioned that the device F swings upward and the rear parts of the pan and machine swing downward, so that ultimately the position indicated in Fig. 24 is 50 reached. Then the machine can be swung around into the position shown in Fig. 14 and finally moved backward to cause the parts to be locked against swinging. After this has been done the chain 12 can be again 55 put in place and the whole apparatus is ready for transportation to another place for use.

It will be understood that the two cables 43 and 41, with the respective winding 60 drums therefor are provided so as to give different rates of movements for the machine. When the machine is being moved off from the truck and made ready for cutting and when it is being moved backward 65 onto the truck it can be moved relatively

rapidly. For effecting these movements the cable 43 is used, which is wound upon the relatively rapidly rotating drum 42. However, when the machine is being used for cutting coal it must be fed relatively slowly, 70 and for these slow feeding movements use is made of the cable 41, which is wound on the relatively slowly rotating drum 40.

The machine can be used in ways other than that which I have described above. 75 One of these ways is illustrated in Figs. 25 and 26. The cutting mechanism is moved from the truck in a way similar to that already described and repetition will not be necessary. However, instead of swinging 80 the machine only slightly to one side, as shown in Fig. 15, it is swung to a position approximately at right angles to the track, as shown in Fig. 25. The cutting mechanism can be extended to its outermost position before it comes into contact with the coal face. Then, with the parts properly locked, as heretofore described, the cable 41 is carried around the face of the room and is held by suitable jacks 63, 64, 65 and 66. The 85 cable is wound and the machine is forced to swing bodily around its vertical pivotal axis on the truck, the jacks being removed successively as the machine reaches them in its swing. An intermediate position of the machine is shown in Fig. 26. When the machine has finally completed a semi-circular 90 cut it can be redrawn onto the truck in the manner already described.

It will be observed that in the use of this 100 apparatus, whether according to the method first described or some other method, the mining machine is always ready for instant reloading onto the truck without any tedious intermediate movements to bring it into loading position. The swinging skids can be 105 swung to any angle so as to accommodate the truck to any angular position of the machine relative to the vertical longitudinal axial plane of the truck. In fact, in the 110 preferred embodiment of the invention, the connection between the machine and the truck is never broken and all that is necessary to effect reloading is to properly adjust the cables.

Furthermore, the truck is not depended upon for carrying the weight of the machine during cutting. The machine is supported directly upon the mine floor and is relatively free for movement so as to follow any irregularities. The truck, however, is made use of for guiding and controlling the movement of the machine. The guiding devices E, F and G can be considered as constituting a radius arm pivoted at one end to 115 the truck and secured at the other end to the mining machine. And this radius arm, while permitting relative movements of the mining machine vertically, nevertheless serves to rigidly hold it up to its work. 120 125 130

Heretofore, in the operation of mining machines of the "short wall" type, reliance had to be placed upon some specially provided parts anchored externally to the machine 5 itself for holding the machine at the proper angle to the coal face. Sometimes reliance was placed upon a special track, or its equivalent, parallel to the face, and sometimes upon a system of cables, or their 10 equivalents. By the present invention I have provided a machine which is self-contained and which is held up to its work by its own constituent parts, assisted only by the main central track, which must be provided in any case.

I do not herein claim any of the novel features of construction embodied in the truck part of the apparatus by itself considered, having filed an application as a 20 division hereof, namely, 338,205, on November 15th, 1919, wherein I present claims relating to some of the features of novelty embodied in the truck part of the apparatus and having also filed an application, 132,682 25 on November 21, 1916, wherein claims are presented for others of the novel features of structure of the truck. The claims herein pertain to a kerf cutting apparatus arranged to be put in operation, and to be 30 related to its work, in the manner set forth, and to be taken from the truck to its working points, and to be returned thereto and transported therewith in the manner described.

35 What I claim is:

1. In a mining apparatus for forming a horizontal kerf in the face of the coal, the combination of a transporting truck element adapted to travel over mine tracks, a kerf 40 cutting element having a cutting mechanism and power drive mechanism and adapted to rest in a predetermined position on the truck and to move off the truck and advance bodily along the coal face to cut a kerf at 45 the floor level, and an intermediate guiding element between the truck and cutting element movable transversely of and relatively to the truck and adapted to be engaged with the cutting element at any of several 50 positions along the coal face to guide said element from any of said positions to the predetermined position on the truck.

2. In a mining apparatus, the combination of a wheeled truck adapted to travel 55 over mine tracks, a complete separately operable mining machine adapted to be supported on the truck above the floor level or independently thereof at the floor level and having a horizontally projecting kerf cutting 60 mechanism, skids connected to the truck with freedom to swing laterally in relation thereto and adapted to be engaged by the mining machine for guidance off from or onto the truck to or from any of several an-

gular positions at the floor level in which 65 it may be independently supported, and means for moving the machine, while it is independently supported and engaged by the skids, transversely of the truck to cut a horizontal kerf under the coal. 70

3. In a mining apparatus, the combination of a wheeled truck adapted to travel over mine tracks, a complete separately operable mining machine adapted to be supported on the truck above the floor level or independently thereof at the floor level and having a horizontally projecting kerf cutting mechanism, skids connected to the truck with freedom to swing laterally in relation thereto and adapted to be engaged by the mining 75 machine for guidance off from or onto the truck to or from any of several angular positions at the floor level in which it may be independently supported, means for moving the machine, while it is independently supported and engaged by the skid, transversely of the truck to cut a horizontal kerf under the coal, and power means for moving the machine along the skids. 80 85

4. In a mining apparatus, the combination of a wheeled truck adapted to travel over mine tracks, a complete separately operable mining machine adapted to be supported on the truck or independently thereof and having a horizontally projecting kerf cutting 95 mechanism, skid devices connected to the truck with freedom to swing laterally in relation thereto and adapted to be engaged by the mining machine for guidance off from or onto the truck to or from any of several 100 angular positions in which it may be independently supported, the said devices comprising at least three parts connected together by at least two horizontal pivoted joints, and means for moving the machine, 105 while it is independently supported and engaged by the skids, transversely of the truck to cut a horizontal kerf under the coal.

5. In a mining apparatus, the combination of a wheeled truck adapted to travel over mine tracks, a complete separately operable mining machine adapted to be supported on the truck above the floor level or independently thereof at the floor level and having a horizontally projecting kerf cutting mechanism, extensible skid devices connected to the truck with freedom to swing laterally in relation thereto and adapted to be engaged by the mining machine for guidance off from or onto the truck to or from any of 110 several angular positions at the floor level in which it may be independently supported, and means for moving the machine, while it is independently supported and engaged by the skids, transversely of the truck to cut a 115 horizontal kerf under the coal. 120

6. In a mining machine, the combination of a wheeled truck adapted to travel over

- mine tracks, a complete separately operable mining machine adapted to be supported on the truck or independently thereof and having a horizontally projecting kerf cutting mechanism, extensible telescopically engaging skid devices connected to the truck with freedom to swing laterally in relation thereto and adapted to be engaged by the mining machine for guidance off from or onto the truck to or from any of several angular positions in which it may be independently supported, means for moving the machine, while it is independently supported and engaged by the skids, transversely of the truck 15 to cut a horizontal kerf under the coal.
7. In a mining apparatus, the combination of a bodily movable wheel supported abutment frame adapted to be anchored in a fixed position, a complete separately operable mining machine having its weight supported independently of the abutment frame and having a bed frame and a kerf cutting mechanism projecting horizontally therefrom, and means connected with the abutment and engaging the mining machine bed frame to guide it transversely in a path fixed relatively to the abutment.
8. In a mining apparatus, the combination of a bodily movable wheel supported abutment frame adapted to be anchored in a fixed position, a complete separately operable mining machine having its weight supported independently of the abutment frame and having a relatively fixed horizontally projecting kerf cutting mechanism, and means connected with the abutment and engaging the mining machine to guide it transversely in a path fixed relatively to the abutment.
9. In a mining apparatus, the combination of a bodily movable wheel supported abutment frame adapted to be anchored in a fixed position, a complete separately operable mining machine having its weight supported independently of the abutment frame and having a horizontally projecting kerf cutting mechanism, means connected with the abutment and engaging the mining machine to guide it transversely in a path fixed relatively to the abutment to make a transverse cut, and means for moving the cutting mechanism forward relatively to the guiding means to make a sumping cut.
10. In a mining apparatus, the combination of a bodily movable wheel supported abutment frame adapted to be anchored in a fixed position, a complete separately operable mining machine having its weight supported independently of the abutment frame and having a relatively fixed horizontally projecting kerf cutting mechanism, means connected with the abutment and engaging the mining machine to guide it transversely in a path fixed relatively to the abutment to make a transverse cut, and means for moving the mining machine bodily forward relatively to the guiding means to make a transverse cut, and means for moving the mining machine bodily forward relatively to the guiding means to make a sumping cut.
11. In a mining apparatus, the combination of an abutment frame adapted to be anchored in a fixed position, a complete separately operable mining machine having its weight supported independently of the abutment frame and having a horizontally projecting kerf cutting mechanism, and means pivotally connected with the abutment and engaging the mining machine to guide it transversely in an arcuate path fixed relatively to the abutment.
12. In a mining apparatus, the combination of an abutment frame adapted to be anchored in a fixed position, a complete separately operable mining machine having its weight supported independently of the abutment frame and having a horizontally projecting kerf cutting mechanism, means pivotally connected with the abutment and engaging the mining machine to guide it transversely in an arcuate path fixed relatively to the abutment to make a transverse cut, and means for moving the cutting mechanism outward relatively to the guiding means to make a sumping cut.
13. In a mining apparatus, the combination of a wheeled truck, a complete separately operable mining machine adapted to be supported on the truck or independently thereof and having a horizontally projecting kerf cutting mechanism, and means connected with the truck and engaging the mining machine while it is independently supported to guide it transversely in a path fixed relatively to the truck.
14. In a mining apparatus, the combination of a wheeled truck, a complete separately operable mining machine adapted to be supported on the truck or independently thereof and having a horizontally projecting kerf cutting mechanism, means connected with the truck and engaging the mining machine while it is independently supported to guide it transversely in a path fixed relatively to the truck to make a transverse cut, and means for moving the mining machine forward relatively to the guiding means to make a sumping cut.
15. In a mining apparatus, the combination of a wheeled truck, a complete separately operable mining machine adapted to be supported on the truck or independently thereof and having a horizontally projecting kerf cutting mechanism, and means pivotally connected with the truck and engaging the mining machine when it is independently supported to guide it transversely in an arcuate path fixed relatively to the truck.
16. In a mining apparatus, the combination of a wheeled truck, a complete sepa-

rately operable mining machine adapted to be supported on the truck or independently thereof and having a horizontally projecting kerf cutting mechanism, extensible devices pivotally connected with the truck and engaging the mining machine to guide it off from or onto the truck to or from any of several angular positions in which it may be independently supported, and means adapted to be engaged by the mining machine to cause telescoping of the said devices as the machine is moved off from or onto the truck.

17. In a mining apparatus, the combination of a wheeled truck, a complete separately operable mining machine adapted to be supported on the truck or independently thereof and having a horizontally projecting cutting mechanism, and means pivotally connected with the truck and engaging the mining machine to guide it transversely while independently supported, the said means being also adapted to engage the mining machine to guide it off from or onto the truck to or from any of several angular positions in which it may be independently supported.

18. In a mining apparatus, the combination of a wheeled truck adapted to travel over mine tracks, a kerf cutter adapted to be supported on the truck or independently thereof and having a horizontally projecting cutting mechanism, and means forming a connection between the truck and the cutter when the latter is supported either on the truck or independently thereof, the said means having a vertical pivotal connection with the truck and having two horizontal pivotal joints which are disposed between the truck and the cutter when the latter is independently supported.

19. In a mining apparatus, the combination of a wheeled truck adapted to travel over mine tracks, a complete separately operable mining machine adapted to be supported on the truck or independently thereof and having a horizontally projecting cutting mechanism, and means forming a connection between the truck and the mining machine when the latter is supported either on the truck or independently thereof, the said means having a vertical pivotal connection with the truck and having two horizontal pivotal joints which are disposed between the truck and the mining machine when the latter is independently supported.

20. In a mining apparatus, the combination of a wheeled truck, a kerf cutter adapted to be supported on the truck or independently thereof and having a horizontally projecting cutting mechanism, a supporting pan along which the cutter is slidable forward and backward, and guide devices having a vertical pivotal connection with the truck and having two horizontal pivotal joints

between the truck and the pan, the said guide devices serving with the pan to guide the cutter transversely when independently supported and also to guide the cutter from or onto the truck to or from any of several angular positions in which it may be independently supported.

21. In a mining apparatus, the combination of a wheeled truck, a complete separately operable mining machine adapted to be supported on the truck or independently thereof and having a horizontally projecting cutting mechanism, a supporting pan along which the mining machine is slidable forward and backward, and guide devices having a vertical pivotal connection with the truck and having two horizontal pivotal joints between the truck and the pan, the said guide devices serving with the pan to guide the mining machine transversely when independently supported and also to guide the said machine from or onto the truck to or from any of several angular positions in which it may be independently supported.

22. In a mining apparatus, the combination of a wheeled truck, a kerf cutter adapted to be supported on the truck or independently thereof and having a horizontally projecting cutting mechanism, a supporting pan along which the cutter is slidable forward and backward, and guide devices having a vertical pivotal connection with the truck and having two horizontal pivotal joints between the truck and the pan, the said pan being slidable onto and off from the truck along the said guide devices and the said guide devices serving with the pan to guide the cutter transversely when independently supported.

23. In a mining apparatus, the combination of a wheeled truck, a kerf cutter adapted to be supported on the truck or independently thereof and having a horizontally projecting cutting mechanism, means pivotally connected with the truck and engaging the cutter when it is independently supported to guide it transversely in an arcuate path fixed relatively to the truck, and a non-rotary element on the truck in the axis of the pivotal connection and adapted to be engaged by a jack for holding the truck against movement.

24. In a mining apparatus, the combination of a wheeled truck, a kerf cutter adapted to be supported on the truck or independently thereof and having a horizontally projecting cutting mechanism, extensible guide devices pivotally connected with the truck and engaging the cutter to guide it transversely while independently supported, the said devices being also adapted to engage the cutter to guide it off from or onto the truck to or from any of several angular positions in which it may be independently supported,

- and means on the truck for transmitting power from the mining machine to the truck wheels when the machine is supported on the truck.
- 5 25. In a mining apparatus, the combination of a laterally cutting mining machine, a wheeled truck adapted to travel over mine tracks, and skid devices pivotally connected to the truck with freedom to swing laterally 10 in relation thereto and adapted to be permanently engaged by a mining machine such as aforesaid for guidance off from or onto the truck to or from any of several angular positions at the floor level in which it 15 may be independently supported, the said devices comprising at least three parts connected together by at least two horizontal pivotal joints.
26. In a mining apparatus adapted to 20 form an arc shaped kerf, the combination of a laterally movable continuously operating kerf cutting machine, a wheeled truck adapted to travel over mine tracks, a pan adapted to slidably support a kerf-cutting 25 mining machine for movement forward and backward, means for positively holding the kerf cutting machine against movement on the pan while the cutter is at work, and guide devices having a vertical pivotal connection with the truck and having two horizontal pivotal joints between the truck and the pan, the said devices serving with the pan to guide the mining machine transversely in relation to the truck on curved 30 lines while supported as aforesaid.
27. In a mining apparatus adapted to 35 form an arc shaped cut near the floor of the mine, the combination of a laterally movable continuously operating kerf cutting machine; a wheeled truck adapted to travel over mine tracks, a pan adapted to slidably support a kerf-cutting mining machine for movement forward and backward, and guide devices engaging the pan and having a vertical pivotal connection with the truck, the said pan being slidable onto and off from the truck along the said guide devices, means for locking the kerf cutter against longitudinal movement on the pan when the 40 kerf cutting mechanism is operating and the said guide devices serving with the pan to guide the mining machine transversely in relation to the truck while the pan is off the truck.
- 50 28. In a mining apparatus for cutting a horizontal undercut transversely of the front face of a mine room, the combination of an abutment, means for holding the abutment against transverse movement, a complete 55 separately operable mining machine having its weight supported independently of the abutment and having a horizontally projecting kerf cutting mechanism, and means pivotally connected with the abut- 60 ment and engaging the mining machine to 65 guide it transversely.
29. In a mining apparatus for cutting a horizontal undercut transversely of the front face of a mine room, the combination of a wheeled truck adapted to be supported 70 on a longitudinal central track, a complete separately operable mining machine adapted to be supported on the truck or independently thereof and having a horizontally projecting kerf cutting mechanism, and 75 means pivotally connected with the truck and engaging the mining machine while it is independently supported to guide it transversely.
30. In a mining apparatus the combina- 80 tion of a kerf cutter, comprising a bed frame, a cutting apparatus and power trans- 85 mitting gearing on said bed frame, the truck, and the guide mechanism permanently engaging with the kerf cutter having a section adapted to lie approximately horizontal on the ground, an inclined section, and a second approximately horizontal section on top of the truck along which sections the kerf cutter can successively move bodily 90 while passing from a position above the truck to a position near the ground.
31. In a mining apparatus the combina- 95 tion of a kerf cutter, comprising a bed frame, a cutting apparatus and power trans- 100 mitting gearing on said bed frame, the truck, and the guide along which the kerf cutter can bodily move while remaining permanently in engagement therewith, said guide being adapted to be put in different angular positions relatively to the truck while the latter remains bodily fixed and having the forward floor supported section, the inclined section and the upper horizontal section sup- 105 ported over the wheel base of the truck.
32. In a mining apparatus, the combina- 110 tion of the kerf cutter, comprising a bed frame, a cutting apparatus and power trans- 115 mitting gearing on the bed frame, the truck, and the guide with which the kerf cutter constantly engages and along which it can bodily move, said guide having a front section adapted to be supported on the ground, an inclined section and a third section sup- 120 ported on the top of the truck, the front section and the inclined section being respec- 125 tively movable in relation to the section on the truck and the guide as an entirety being movable laterally relatively to the truck.
33. In a mining apparatus the combina- 120 tion of the kerf cutter, comprising a bed frame, a cutting apparatus and power trans- 125 mitting gearing mounted on said bed frame, the truck, and the guide with which the kerf cutter constantly engages and along which it can bodily move, said guide comprising three sections connected together, the front section being movable longitudinally as to

the second and the third sections, the third section being supported on the truck, and the second being hinged relatively to the third.

5. 34. In a mining apparatus, the combination of the kerf cutter, comprising a bed frame, a cutting apparatus and power transmitting gearing mounted on said bed frame, the truck, and the guide with which the kerf cutter constantly engages and along which it can bodily move, said guide being formed in three sections connected together, the first section being adapted to rest upon the ground, the third section being adjustably mounted on the truck, and the second section being adjustably connected to the third and to the first.

35. In a mining apparatus, the combination of the kerf cutter comprising a bed frame, a cutting apparatus and power transmitting gearing mounted on said bed frame, the truck, and the guide permanently connected to and movable with the kerf cutter relatively to the truck when the cutter is in operation, said guide having a front section adapted to rest upon the ground, a section pivotally connected to the truck and an intermediate section flexibly connected to both of the aforesaid sections to permit it to assume different angular operative positions relatively to the other said sections.

36. In a mining apparatus, the combination of the kerf cutter comprising a bed frame, cutting apparatus and power transmitting gearing mounted on said frame, the truck, and the longitudinally extensible guide permanently connected to the kerf cutter and formed in a series of sections one of which while engaging with the kerf cut-

ter is adapted to be superposed upon the other sections while they are all connected together.

37. In a mining apparatus, the combination of a kerf cutter comprising a bed frame, cutting apparatus and power transmitting gearing mounted on said frame, the truck, and the guide adapted to be permanently connected to the kerf cutter and made in three permanently connected sections, namely, a front section adapted to rest upon the ground, a section supported on the truck and an intermediate section adapted to be inclined relatively to both of the other sections, and the first aforesaid section being longitudinally adjustable to a position where it is superposed upon the other two sections.

38. In a mining apparatus, the combination of the kerf cutter comprising a bed frame, cutting apparatus and power transmitting gearing mounted on said frame, the truck, and the guide adapted to engage permanently with the kerf cutter and to rotate around the truck while the latter is held stationary, said guide being made in a series of sections, each vertically movable with respect to the next and adapted to permit the kerf cutter to take either of several angular positions relatively to the horizontal and either of several angular positions relatively to the truck.

In testimony whereof, I affix my signature, in presence of two witnesses.

NILS D. LEVIN.
